UNITED STATES PATENT OFFICE.

CASPER HUGO GRINGS, OF WATERLOO, IOWA, ASSIGNOR TO WATERLOO SADDLERY COMPANY, OF WATERLOO, IOWA.

HORSE-COLLAR PAD.

Application filed July 16, 1923. Serial No. 651,946.

To all whom it may concern:

Be it known that I, CASPER HUGO GRINGS, a citizen of the United States of America, and a resident of Waterloo, Blackhawk County, Iowa, have invented certain new and useful Improvements in Horse-Collar Pads, of which the following is a specification.

My invention relates to improvements in horse-collar pads, and the object of my improvement is to provide a rigid liner plate for a cushion envelope pad, the plate having means for anchoring it to the envelope against change of relative position, and other securing means connected to the pad thereby for releasably fastening an adjustable billet-strap thereto.

This object I have accomplished by the means which are hereinafter described and claimed, and which are illustrated in the accompanying drawings, and it is to be understood that minor variations in said means are included within this invention.

Fig. 1 is a fragmental view of a horse-collar showing my improved pad and securing means mounted in its neck portion. Fig. 2 is an enlarged section through the medial part of the pad and the billet securing means. Fig. 3 is a perspective view of the pad with a part broken away. Fig. 4 is a like view of the pad, showing in addition the billet securing means. Fig. 5 is a plane view of the eared plate before bending. Fig. 6 is a plan view of the eared plate mounted upon the pad. Fig. 7 is a plan of part of the pad, showing the hooked projections of the liner protruding thereabove. Fig. 8 is a section of the middle of the pad, showing said projections disposed as in Fig. 7.

The pad is of the arched and transversely dished or concaved shape of the usual type to fit within the neck part of a collar. It is composed of a rigid metal plate serving as a stiffening liner and which is completely enclosed by a flexible cushioning envelope preferably made of a like pair of soft leather parts 2 and 3 placed upon the upper and under faces of the said liner plate 1, but of a little larger size to permit of stitching

their margins together around the plate, as shown at 9.

The liner plate 1 has a pair of partially punched out projections along its median line bent upwardly at 4 and having their extremities 5 bent towards each other, and these hooks serve to clip and engage the top part 2 of the envelope to anchor the plate 1 in position against any shifting therein.

The plate 1 and the pad part 2 may be orificed in line between said projections 4—5 to receive the pin 6, to project thereabove, the flat head 7 of the pin being positioned between the lower face of the plate and the lower pad part 3. A small rectangular plate 13 may have a central hole 16 to seat it upon said pin with opposite margins of the plate clipped and secured by the hooked projections 4—5. Other opposite parts 14 of the plate 13 are bent upwardly slopingly and provided with slots 15, so that an adjustable double-ended billet-strap 8 may have its middle part passed through said slots so that its ends may be secured to the collar buckles 11 adjustingly to keep the pad 75 properly centered.

A small spacing sleeve 17 is fixed upon the pin 6 to uphold the strap 8 medially.

This permits the pad to be used either with or without the billet securing means as desired according to the type of collar and neck flap connections in use.

Having described my invention, what I claim as new, and desire to secure by Letters Patent, is:

1. A horse-collar pad, comprising a rigid liner plate having a pair of projections thereon spaced apart in the medial line of the plate, and a cushioning envelope of flexible material covering said plate and apertured to receive said projections, the projecting ends of the projections being hooked over upon the envelope to anchor the plate thereto in one position preventing creeping thereon of the envelope.

2. A horse-collar pad, comprising a rigid metal liner plate having a pair of hooked projections and an orifice intermediate the projections, a cushioning envelope covering said plate and provided with apertures in

85

line with said projections and said orifice, a headed pin traversing the orifice in the plate and the aligned aperture in the envelope, a member orificed to receive said pin there-
through and having opposite margins en-
gaged by said hooked projections, other
margins of said member being bent up-
wardly and slotted in line to receive a billet-

strap, and a spacing-body mounted on said pin above said member to support the strap 10 medially, the extremity of the pin being inserted in a hole in said strap.

Signed at Waterloo, Iowa, this 30th day of June, 1923.

CASPER HUGO GRINGS.
